UNITED STATES PATENT OFFICE.

JOSEPH MONFORTS, OF MUNICH-GLADBACH, GERMANY.

FABRIC-SHEARING MACHINE.

Application filed April 13, 1925, Serial No. 22,897, and in Germany May 13, 1924.

A common defect of machines for shearing fabrics is that the actuating mechanism for the knife cylinders and drum is comparatively complicated, there being too many shafts, pulleys, belts and other parts in the under frame of the machine, which parts are obstructive when the cloth is being inserted or when any other operation has to be performed in connection with the under frame.

According to this invention this defect is removed by driving the knife cylinders by means of an electromotor carried by a pivoted arm, which can rotate vertically and is suspended in a loop of the driving belt. With this arrangement the motor tensions the belt, but yields when the cylinders are lifted. The fabric drum may be driven by means of a pulley suspended in another loop of the belt.

The invention is illustrated diagrammatically in the annexed drawings, which show three examples in Figs. 1, 2 and 3 respectively.

In the example shown in Fig. 1 *a* designates the shearing knives, which are driven collectively by a belt *b*. The belt forms a suspended loop, in which is hung the motor *c*, carried by an arm *e* pivoted at *d*. The weight of the motor is sufficient to tension the belt, but weight may be added. *f* designates the fabric to be treated. For driving the drum *g* the belt may at the top form a second loop *b*¹, as indicated by a broken line, there being in this loop a pulley *h*, which drives the drum by means of a belt or chain and also holds the driving belt *b* in contact with a larger portion of the knife cylinders.

In the example shown in Fig. 2 there are three knife cylinders *a*, the arrangement be-

ing otherwise similar. In order to have the contact surface of the belt approximately uniform in the case of each cylinder a pulley *i* is disposed symmetrically in relation to the pulley *h*.

In the example shown in Fig. 3 there are two pairs of knife cylinders *a* driven collectively by a single belt *b* and an electromotor *c*. For treating the fabric on both sides the two pairs of cylinders must rotate in opposite directions. For this purpose the belt *b* passes from the right hand pair of cylinders round a pulley *h* and thence to the left hand pair of cylinders. The pulley *h* suspended in the looped belt drives the two fabric drums *g*, *g'* by means of gear wheels *j*, *l*, *m*, *n*, *o*. It will be seen that even with four knife cylinders the actuating mechanism is very simple; the weight of the motor serves to tension the belt and keep it uniformly taut.

What I claim is:

1. Driving means for fabric shearing machines having a plurality of independently movable knife cylinders, comprising pulleys on said cylinders, a single belt engaging all said pulleys, and a swingably mounted electromotor having a pulley hanging in said belt.

2. Driving means for fabric shearing machines having independently movable knife cylinders and a fabric drum, comprising pulleys on said cylinders and drum, a single belt engaging all said pulleys, and a swingably mounted electromotor having a pulley hanging in said belt.

The foregoing specification signed at Berlin, Germany, this 20th day of March, 1925.

JOS. MONFORTS.
